UNITED STATES PATENT OFFICE.

CHARLES R. HARRIS, OF WILLIAMSPORT, PENNSYLVANIA.

DESIGN FOR A BICYCLE-FRAME.

SPECIFICATION forming part of Design No. 26,590, dated February 2, 1897.

Application filed January 6, 1897. Serial No. 618,207. Term of patent 14 years.

To all whom it may concern:

Be it known that I, CHARLES R. HARRIS, a citizen of the United States, residing at Williamsport, in the county of Lycoming and State of Pennsylvania, have invented and produced a new and original Design for Bicycle-Frames, of which the following is a specification, reference being had to the accompanying drawing, forming a part thereof.

10 The accompanying drawing illustrates my design.

The leading feature of my design consists of a bicycle-frame having a continuous unbroken curved outline, resembling in outline 15 the general form of a phaeton.

A represents the steering-head of a bicycle, and B the frame. Starting at the point *a* the frame is bent gradually downward and then upwardly in a general curved direction until 20 it reaches its highest point at a position above the wheel, as at *b*. Then the frame is bent downwardly in front of the rear wheel and

finally upwardly and joined to the frame. In addition to the main portion thus described a longitudinal bar of tubing *c* extends from 25 the steering-head rearward to a point where it is joined to the main frame, as at *d*, and from this point the bar is bent upward, forming a socket for the seat-post.

The rear of the main frame is divided to 30 straddle the rear wheel, as shown, and the tubing constituting this divided portion merges into a single bar forward, and in the space formed between the converging portion of the frame the drive-shaft and sprocket-wheel are 35 journaled.

What I claim is—

The design for a bicycle-frame herein shown and described.

CHAS. R. HARRIS.
